(57) **CLAIM**

The ornamental design for a cutting tool, as shown and described.

DESCRIPTION

FIG. 1 is a front elevational view of a cutting tool in accordance with a first embodiment of the present design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 shows the cutting tool in an environment of use thereof;

FIG. 10 is a front elevational view of a cutting tool in accordance with a second embodiment of the present design;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof;

FIG. 16 is a first perspective view thereof;

FIG. 17 is a second perspective view thereof; and,

FIG. 18 shows the cutting tool in an environment of use thereof.

The broken lines shown in FIGS. 9 and 18 represent environment portions that form no part of the claimed design.
